OIL BURNER IGNITING MECHANISM

Rene M. Vidalie, Port Washington, N. Y., assignor
to Preferred Utilities Company, Inc., New York,
N. Y., a corporation of Delaware

Application June 21, 1938, Serial No. 215,007

21 Claims. (Cl. 158—28)

This invention relates to ignition mechanism for oil burners and has particular reference to rotary type burners wherein oil is discharged from a fuel tube fixedly positioned within a rotating oil cup and centrifuged into a swirling current of air to form a combustible mixture. It is applicable to the air turbine driven type rotary burner as well as to the horizontal and vertical motor driven types of rotary burner.

10 For domestic purposes the so-called gun type burner has hitherto been used very extensively. The ignition associated with this type of burner, wherein oil is supplied to a nozzle at high pressure and atomized as it is discharged therefrom, air 15 being supplied around the spray through a blast tube from a blower, is obtained from a high tension spark.

The rotary type of burner possesses many inherent advantages suiting it to use for domestic 20 purposes by reason of its low cost of manufacture, efficiency of combustion, and the fact that its fire may be varied within a large range without change of parts simply by simultaneous positioning of the air and oil valves. This produces a 25 flexibility unobtainable with the gun type burner and permits what may be regarded as "modulating flame control," a very important feature when considering the ultimate burner control whereby the fire is controlled directly and instantly by the 30 load as distinguished from the very severe and inefficient "on" and "off" operation.

A further advantage in the rotary burner resides in the fact that it can be efficiently operated at a relatively low rate of combustion, being capable of sustaining a fire on approximately one 35 quart of oil per hour as compared with from three quarts to one gallon of oil per hour necessary for the gun type.

High tension spark ignition has not proved 40 suitable for oil burners of the rotary type and an object of this invention is to provide efficient automatic electric ignition for a rotary burner, automatically operable to provide reliable and safe ignition under all circumstances.

45 Another object of the invention is to so construct and arrange the ignition mechanism in association with the rotary type burner that no heavy carbon deposit forms in the oil cup after the repeated firing and dousing of the burner that 50 is essential for satisfactory domestic use. Service cost, upkeep, and incidental annoyances to the domestic user are thereby eliminated and the rotary type of burner with its attendant efficiency and flexibility is available in a field wherein it 55 has been hitherto relatively unknown.

A distinct advantage in my improved ignition mechanism resides in the fact that it functions without creating radio interference, which is sometimes very troublesome with high tension spark ignition and becomes especially so with the 5 appearance of extra-sensitive sets for short wave lengths and television.

An important feature of the invention resides in the particular method whereby the above specified advantages, together with others hereinafter 10 to be brought out, are obtained. Elimination of dangerous explosions as well as promptness and reliability in performing the ignition function are obtained by first heating the oil rendered available through the discharge opening in the fuel 15 tube to a temperature above the flash point of the oil, thereby vaporizing the same, and subsequently igniting the vapor so formed through the same heating element which created the vaporization. For this purpose it is of course necessary 20 to locate the heat source, here shown in the form of an electrical resistance element, near the discharge opening in the fuel feed tube and so associate it with the surrounding mechanism that the heat radiated thereby may be used for the 25 purpose of initially vaporizing the oil.

To this end I have provided an electric circuit including a resistance coil positioned within the oil cup on the discharge side of the fuel feed tube opening. The heat from the resistance coil is 30 absorbed by the walls of the oil cup to thereby vaporize the oil fed thereinto through the fuel tube discharge opening. The vapors so formed within the oil cup are ignited by direct contact with the resistance element, and air is supplied in 35 the usual manner to maintain combustion.

Performance of this method is considerably facilitated under certain circumstances when the oil cup itself is shielded or insulated from the blast of air customarily surrounding the same. For 40 this purpose I have provided an insulating sleeve surrounding the oil cup and protecting the same from the air blast. In this manner the time required to bring the oil cup up to a temperature 45 reduced and ignition is obtained more quickly, particularly where the oil is turned on after previously starting both the ignition and air blast.

Among other objects of the invention are to so 50 arrange the discharge opening in the fuel feed tube as to preclude the possibility of oil seeping or drooling along the fuel tube, in either direction, when the oil supply is shut off. This aids materially in preventing the formation of carbon or soot on the walls of the oil cup.

Various other objects and meritorious features of the invention will become apparent from the following description taken in conjunction with the drawings, wherein like numerals refer to like parts throughout the several figures, and wherein:

5 Figure 1 is a side elevation, broken away and in section, of the front end of a typical installation;

10 Fig. 2 is a fragmentary section through the oil feed head at the rear of the burner;

15 Fig. 3 is a sectional view similar to Fig. 1 illustrating a modified form of structure;

20 Fig. 4 is a section through the oil feed head of the modified form illustrated in Fig. 3;

25 Fig. 5 is an enlarged partially sectional view 15 of my improved resistance coil assembly;

Fig. 6 is a somewhat diagrammatic view of the 20 improved ignition associated with a rotary burner of the vertical type;

25 Fig. 7 is a section illustrating a somewhat modified form of resistance coil igniter;

30 Fig. 8 is a sectional view illustrating my improved ignition mechanism associated with an air turbine driven rotary burner, and

35 Fig. 9 is a diagrammatic illustration of a conventional program relay circuit for relative timing 25 of the motor, ignition element, and oil feed operations.

Referring now to Figs. 1 and 2 of the drawings, the numeral 18 represents the outer casing of a 30 rotary oil burner of the horizontal type in which the motor 12 is provided with a hollow armature shaft 14 through which the fuel feed tube 16 extends. The fuel feed tube is fixedly positioned by the oil feed head 18 and is preferably welded 35 thereto as at 22. The head is bolted as at 20 to the rear of the motor casing.

Hub member 24 is bolted to the front end of motor shaft 14 and is provided with a flange 26 to which is secured, as by means of rivets 28 or 40 otherwise, fan member 30. A casing cover 32 is secured to the open face of the casing 18, which cover includes a diaphragm portion 34 which functions as a baffle in directing the forced air around the oil cup and through the burner mouth.

45 In the preferred form illustrated in Figs. 1 and 2 the oil cup is so formed as to provide an annular dead air space surrounding it, thereby insulating the inside wall of the cup from the secondary air blast passing around it when the motor is in 50 operation. The cup comprises an inner tapered member 36, which is preferably of high grade bronze having a low specific heat, provided with annular flanges 38 and 40 at each end. A cylindrical tube 42, which is preferably stainless steel 55 having a low heat conductivity, is press-fitted over the flanges 38 and 40 and bolted to hub member 24 as indicated at 44. It is immaterial how tapered insert or cup 36 is fixed in the surrounding tube 42, the important feature being the formation of a dead air space surrounding the cup 36 and completely sealed from ingress of moisture and air. The annular flanges 38 and 40 may be received in a press fit by outer tube 42, or possibly 60 welded thereto, to perform this function in the arrangement illustrated.

65 The air blast from fan 30 passes through the burner mouth at the discharge end of the oil cup, being deflected during its passage therethrough by means of an internally rifled bushing indicated at 46.

An electrode rod 48 is fixedly positioned within the fuel tube substantially centrally thereof. One end may be positioned at the rear of the oil feed head by means of a contact member 50 bolted 70 thereto as at 52 which is insulated from the feed

head by an annular insulating member 54. Electrode rod 48 extends through the fuel feed tube and is supported at its forward end by means hereafter described. One end of resistance coil 56 is connected to the forward end of rod 48 and its other end is connected, directly or indirectly, to the fuel feed tube. The fuel feed tube provides a return circuit from the resistance coil, which circuit is grounded through the motor casing by the contact indicated at 58.

10 Flow of oil through passage 68 in the oil feed head may be controlled by a valve operating member 62. It is to be noted that the central electrode rod 48 projects beyond the end of the fuel feed tube and extends substantially to the discharge 15 end of the oil cup. The annular passage within the fuel tube surrounding the electrode rod, through which the oil supply flows, is closed just beyond the discharge opening 64 and the forward end of said rod is supported by means of fuel tube 20 tip 66, more fully illustrated in Fig. 5.

25 Central electrode 48 is preferably of nickel wire and should be a fairly good conductor, substantially impervious to corrosion from fuel oil fumes containing small amounts of sulphur, and heat 30 resisting to a substantial extent. The aforesaid fuel tube tip 66 may comprise a metallic or conducting tube 68 having an annular lip portion 70 press-fitted into a corresponding annular lip 72 formed at the extremity of fuel feed tube 16. For 35 integrating and rigidifying purposes bead 74 extending around the wall of the tube and abutting lip 72 may be welded or brazed to the said lip as indicated at 73. An opening 76 is provided on the upper side of tube 68 for discharge of the fuel 40 into the oil cup and annular beads 78 and 80 45 adjoin this opening on each side thereof. Beads 74, 78, and 80 function to prevent oil dripping or 50 drooling back along the tube toward the motor shaft or into the oil cup and, by placing opening 76 on the upper side, accumulation of oil in the 55 cup during the shut-off period is substantially 60 eliminated.

55 The forward end of tube 68 is provided with an annular flange 81, which performs the same function in preventing seepage as beads 74, etc., and which includes a socket member 82 adapted to receive therein one extremity of resistance coil 56, which is preferably welded therein as indicated at 84. The other end of the resistance coil is inserted in a socket 85 provided in the end of central electrode 48 and is likewise preferably welded 65 therein as indicated at 86. A centrally apertured disc 88 of ceramic material which is insulating and heat resisting is inserted into the end of tube 68 and around electrode rod 48 on the forward side of discharge opening 76. This disc is cemented in as indicated at 90 with material which is also insulating and heat resisting, thereby securely sealing the end of the tube beyond the discharge 70 opening thereof, supporting electrode rod 48 within the fuel feed tube, and insulating the one from the other.

75 A somewhat modified form of structure is illustrated in Figs. 3 and 4 wherein a second tube 92 surrounds fuel feed tube 16 and is insulated therefrom by suitable means, such as a mica tube 94. In this modification the fuel feed tube itself constitutes the lead electrode and surrounding tube 92 is the electrode providing for the return 80 circuit which is grounded through the burner casing by contact with the oil feed head as indicated at 96. Contact member 98 surrounds the fuel feed tube to provide a lead-in from some 85 suitable source of electricity, said contact mem- 90

ber being insulated from component parts 100 and 102 of the oil feed head by annular insulating members 104 and 106. The entire assembly may be secured together by means of bolts 108 which are insulated from contact member 98 by means of insulating sleeves, not shown.

The forward end of tube 92 is broken away on its under side as indicated at 110 somewhat short of its extremity to permit free flow of oil through discharge opening 112 in the end of the fuel feed tube. In this particular modification the discharge opening is directed downwardly. Tube 92 terminates at substantially the end of fuel feed tube 16 and rod 114 is press-fitted and welded in the open end of the fuel tube to seal the said tube on the discharge side of opening 112. One end of resistance coil 56 is secured to the end of rod 114 and the other is inserted in a socket 116 formed in any suitable manner at the forward extremity of electrode tube 92.

Thus the circuit to the resistance coil is provided through the fuel tube itself and returned through electrode tube 92, being grounded through the contact of the latter with the oil feed head at the rear of the burner, this circuit being substantially the same as the circuit in the preferred form hitherto described.

Oil cup 118 is press-fitted over a lip 120 of fan hub 122, which latter is secured to the hollow armature shaft 14 of the motor in any suitable fashion. An annular flange 124 abuts against the end of this lip to limit the telescoping movement of the oil cup thereover, as does shoulder 125 of the hub.

A somewhat modified form of insulating sleeve is herein illustrated, the sleeve 126 being welded as indicated at 128 to the flared annular extremity of diaphragm member 34, which constitutes an integral part of casing cover 32. The sleeve is spaced from the wall of oil cup 118 to thereby provide an air space immediately surrounding the same, but the air space is not closed as in the preferred form of structure. Nevertheless, this insulating sleeve shields the oil cup from the air blast from the fan, thereby facilitating heating of the oil cup wall.

In Fig. 6 I have illustrated in somewhat diagrammatic form the application of the hitherto described ignition mechanism to a rotary oil burner of the vertical type. As clearly indicated therein, a central electrode 130 extends through fuel tube 132, which fuel tube functions as the grounded electrode. Rod 130 is insulated as indicated at 134 from the oil feed head 136 supplied through tube 138. The electrode rod 130 projects through and beyond the closed end of the fuel tube and one end of resistance coil 140 is connected to the end thereof and its other end is connected to fuel tube 132 in a manner hitherto described.

This installation as illustrated does not include an insulating sleeve surrounding the oil cup 142, the walls of which are preferably more tapered than the oil cup used in the horizontal type burner so that proper centrifuging of the oil is obtained. The insulating sleeve is not essential to successful performance of my improved method of igniting a rotary oil burner, although it is distinctly advantageous and desirable where, as aforesaid, the ignition and air blast are started simultaneously.

Fig. 7 illustrates a modified form of resistance coil which has proven distinctly advantageous in that it positively prevents the coil from sagging and provides a better insulation between the in-

5
fuel tube tip 66 and where the difference in potential is the highest. One end of resistance coil 144 is inserted in a socket provided in the end of electrode rod 146 and may be welded or soldered therein as indicated at 148. This end of the resistance coil is straight and extends out to approximately the open extremity of the oil cup through an insulating core 150 about which the coil portion of the resistance element is wound. The other end of the coil is secured in a socket 152 provided in the fuel tube tip hitherto described. It is to be noted that core 150 extends into the end of the fuel tube tip but terminates short of the oil discharge opening. A seal 154 of oil-proof and heat-proof cement abuts the 15 end of core 150 and seals the annular discharge portion of the fuel tube on the discharge side of the opening therein.

The composite oil cup is so constructed and arranged in this modification as to provide an 20 annular dead air space surrounding the inner wall of the cup, as hitherto described. The tapered inner member 156 and straight tubular insulating sleeve 158 are secured by means of a series of single rivets 160 to an annular shoulder 25 162 projecting from the fan hub 164. The thickness of this annular shoulder and the taper of member 156 are such that sleeve 158 and member 156 are held in abutting relation at the extremity of the composite cup, thereby creating 30 a dead air insulating space about the inner wall thereof. The abutting ends of member 156 and insulating sleeve 158 may be positively sealed, if desired, in any suitable manner.

Fig. 8 illustrates in section a typical air turbine 35 driven rotary burner having associated therewith the improved ignition mechanism hitherto described. A hollow shaft 166 is rotatably journaled within casing 168. A rotor 170 is fixedly secured to shaft 166 and is rotated by an air blast forced 40 through passage 172 and issuing through nozzle 174 surrounding the rotating oil cup after it has passed the rotor. The composite insulated oil cup 176 is the same as that illustrated in Fig. 7 and described above. Electrode rod 178 extends coaxially through fuel tube 180 in a manner hitherto described, oil flow being controlled from fuel feed head 182. The fuel tube tip 184 and the resistance coil 186 herein illustrated are like those illustrated in Fig. 7 and hitherto described.

The current is preferably supplied by a constant output transformer that gives the same output regardless of primary voltage variations. The secondary current may be about two volts and between fifty and seventy-five amperes, which presents no insulation difficulties throughout the ignition circuit because of the low voltage. A program relay of the conventional type may be arranged for controlling the circuit to the motor, the resistance coil and oil feed in timed relation 55 to one another. The entire fuel feed assembly, including the ignition mechanism, may be removed by unbolting the oil feed head and withdrawing the tube assembly through the hollow motor shaft.

The numeral 192 represents a standard thermostat control, hereafter referred to as the thermostat, which includes a main boiler switch and a thermostat switch, not shown. This unit is customarily placed in the smoke pipe of the furnace 70 where it is most susceptible to effective changes in temperature. The unit is one of several standard manufactured products designed for this particular use.

When predetermined temperature conditions 75

are present the thermostat unit operates to simultaneously close a circuit from main line 186 through 190 and thence out of the unit through leads 194 and 214. A thermostat switch operating transformer in the thermostat unit is grounded to ground wire 188 through lead 220.

Lead 194 feeds a program motor through branch 198, the current passing out through lead 204 to lead 212 which extends back to ground wire 188. The program motor, which is one of many possible standard products available for closing a circuit in timed relation, includes a rotor 200 carrying a cam 202 which is operable on continued rotation of the said rotor to actuate switch arm 196 to thereby make contact with lead 206 extending to oil feed control actuating means 208 and to the motor 210, preferably positioned in a housing indicated by the numeral 222. The circuit through these two units is carried through lead 212 back to ground wire 188.

Lead 214 extending from the thermostat unit 192 energizes the primary coil of a transformer 216 and is grounded through 212 to ground wire 188. The secondary of the transformer feeds ignition resistance coil 56 through lead 218 which is coupled with the electrode rod 48, the return being through the tube 16 which is grounded as indicated at 58 in Figs. 2 and 9, at which point the other end of the secondary coil of the transformer 216 is likewise grounded. The oil feed tube 16 may be grounded elsewhere if desired, as indicated diagrammatically.

From the foregoing it will be apparent that, when leads 214 and 194 are energized simultaneously through thermostat unit 192, the resistance coil 56 is immediately included in circuit and begins to heat the wall of oil cup 36. Simultaneously the rotor 200 of the program motor fed by lead 194 begins to turn. The speed of the rotor is so timed that cam 202 functions to close the circuit through 196 and 206 after approximately sixty seconds, at which time the circuit through oil feed control 208 and the motor 210 is completed. In this way the wall of the rotary oil cup may be heated above the flash temperature of the oil prior to depositing oil thereon and prior to forcing air through the duct surrounding the same. This is an effective means for excluding from contact with the wall of cup 36 any substantial amount of air tending to cool the same during the period of preheating by means of resistance coil 56.

There are two satisfactory cycles for obtaining ignition by my improved method and mechanism. Each has its attendant advantages. The circuit through the igniting resistance coil may first be started, and after a preheating period the circuit to the motor creating the air supply is closed and the oil supply line opened. This particular cycle of operation requires a shorter period of pre-ignition than that described later. When the ignition circuit is closed the resistance coil is heated to about 2000° F. and the radiant heat therefrom is absorbed by the walls of the atomizing cup. When the oil is turned on vapors are formed in the cup because the temperature of the walls is above the flash point of the oil, and these vapors are ignited by direct contact with the resistance coil positioned within the cup. Air for maintaining combustion after igniting the vapor is available simultaneously, the circuit to the motor having been closed when the oil line was opened. With this particular cycle of operation the insulating sleeve surrounding the oil cup is not so particularly desirable because the air blast 75 is not turned on until the walls of the oil cup have

been brought up to a temperature above the flash point of the oil. There has therefore been no cooling blast around the oil cup during the pre-heating stage. It is for this reason that this particular cycle of operation provides the most rapid 5 ignition. Eliminating the air blast during the period when the cup is heating is perhaps a more effective means than a sleeve for excluding from contact with the wall of the cup any substantial amount of air tending to cool the same. 10

The other cycle involves starting the ignition by closing the circuit through the resistance coil and simultaneously starting the air blast by closing the motor circuit. The oil line is then opened after the oil cup has been heated to a 15 temperature above the flash point of the oil. This cycle is particularly advantageous because, although it requires a longer pre-ignition period, the inside of the cup is maintained free and clear of undesirable soot and carbon which might 20 otherwise become deposited on the walls. When the motor and ignition are started together prior to supplying oil to the cup, rotation of the cup purges it of any oil accumulated during the shut-off period and no carbon forms on the walls. A 25 longer pre-ignition period is required, however, because the air blast from the fan begins with rotation of the oil cup and its cooling effect lengthens the time required to heat the wall of the oil cup to a temperature above the flash 30 point of the oil. The difference in time is not great where the insulating sleeve shields the cup from the air blast. After the cup has reached the desired temperature, which may require an approximate maximum of sixty seconds elapsed 35 time, the oil valve is opened and ignition takes place in the same manner as hitherto described. Thus the delay in providing the oil feed permits the oil cup to purge itself and provides time for heating the wall thereof to the desired temperature by means of the radiant heat from the resistance coil positioned within the cup.

It will of course be understood that the ignition circuit is opened automatically by the program relay after ignition has been completed. 45

It is to be noted that where the discharge opening of the fuel tube is at the top, the fuel tube is always full when the oil is shut off, there is no dripping or drooling while the burner is idle, and fuel is available at the cup as soon as the 50 oil valve opens. The beads surrounding the tip of the fuel feed tube, tube 68 illustrated in Fig. 5, prevent oil from running along the tube toward the heating element or toward the hollow motor shaft. 55

In all of the forms illustrated the same method of ignition occurs. The wall of the oil cup is pre-heated by radiant heat from resistance coil to a temperature such that oil introduced into the cup will flash and the vapors formed ignite on 60 contact with the resistance coil, air being provided by the blast issuing through the mouth of the burner to maintain combustion after initial ignition.

While certain preferred forms of the invention have been described and illustrated, various modifications will be apparent to those skilled in the art and for that reason I wish to limit myself only within the scope of the appended claims. 65

What I claim is:

1. A method of igniting an oil burner having a rotary cup which comprises the steps of pre-heating the wall of said cup to a temperature above the flash point of the oil by radiation from a heat source so positioned with reference to the 75

- wall thereof as to preclude contact between the heat source and the wall, and thereafter depositing oil upon the wall of the cup without contacting said oil with the heat source to thereby 5 successively vaporize the oil by contact with the preheated wall and subsequently ignite the vapor so formed by contact with said heat source.
2. A method of igniting an oil burner having a rotary cup surrounded by a forced air duct which 10 comprises the steps of preheating the wall of said cup, while excluding any substantial amount of air tending to cool the same from contact therewith, to a temperature above the flash point of the oil by radiation from a heat source so positioned with reference to the wall thereof as to preclude contact between the heat source and the wall, and thereafter depositing oil upon the wall of the cup without contacting said oil with the heat source to thereby successively vaporize 15 the oil by contact with the preheated wall and subsequently ignite the vapor so formed by contact with said heat source.
3. Ignition mechanism for a rotary oil burner comprising a rotatable oil cup, heating means 20 arranged to heat solely by radiation the inside of the wall of said cup to vaporize oil when deposited thereon, said heating means including an element capable of radiating sufficient heat to raise the inside of the cup wall to a temperature above the flash point of the oil and so positioned as to contact the vapor so formed to ignite the same, and means for depositing oil inside 25 said cup on the wall thereof.
4. Ignition mechanism for a rotary oil burner comprising a rotatable oil cup, an air passage surrounding the same, means for passing air therethrough, means for excluding from contact with the wall of said cup any substantial amount of air tending to cool the same, means for depositing oil inside said cup on the wall thereof, and a heating element so positioned relative to said cup as to heat the inside of the wall thereof to thereby vaporize the oil deposited thereon and contact the vapor so formed to ignite the 30 same.
5. Ignition mechanism for a rotary oil burner comprising a rotatable oil cup insulated exteriorly against heat losses, means for depositing oil inside said cup on the wall thereof, and a heating element so positioned relative to said cup as to heat the inside of the wall thereof to thereby vaporize the oil deposited thereon and contact the vapor so formed to ignite the same.
6. Ignition mechanism for a rotary oil burner including a rotatable oil cup and a fuel tube opening into said cup and comprising a heating element positioned within the cup on the discharge side of said fuel tube opening, and a heat insulating sleeve surrounding said cup.
7. Ignition mechanism for a rotary oil burner including a rotary oil cup, a fuel tube opening into said cup, and a forced air duct surrounding the cup, and comprising a heating element positioned within the cup on the discharge side of said fuel tube opening, and means surrounding said cup to shield the same from the air in said duct.
8. Ignition mechanism for a rotary oil burner including a rotatable oil cup comprising a fuel feed tube opening into said cup and constituting one electrode of an electric circuit, a second electrode spaced therefrom projecting into the oil cup, a resistance coil positioned within the oil cup on the discharge side of the opening in said fuel feed tube connecting the two electrodes, and a 70 heat insulating sleeve surrounding said oil cup.
9. Ignition mechanism for a rotary oil burner including a rotatable oil cup comprising a fuel feed tube opening into said cup and constituting one electrode of an electric circuit, a second electrode spaced therefrom projecting into the oil cup, a resistance coil positioned within the oil cup on the discharge side of the opening in said fuel feed tube connecting the two electrodes, and an insulating sleeve surrounding said oil cup in spaced relation thereto, said sleeve being so constructed and arranged with reference to said cup as to form an annular dead air space surrounding the same.
10. Ignition mechanism for a rotary oil burner including a rotatable oil cup comprising a fuel tube opening into said cup and constituting one electrode of an electric circuit, a tube electrically insulated from and surrounding said fuel tube extending into said oil cup and constituting a second electrode, a resistance coil positioned within said oil cup on the discharge side of the opening in said fuel tube connecting said tubes, and a heat insulating sleeve surrounding said oil cup.
11. Ignition mechanism for a rotary oil burner including a rotatable oil cup comprising a fuel tube opening into said cup and constituting one electrode of an electric circuit, a tube electrically insulated from and surrounding said fuel tube extending into said oil cup and constituting a second electrode, a resistance coil positioned within said oil cup on the discharge side of the opening in said fuel tube connecting said tubes, and an insulating sleeve surrounding said oil cup in spaced relation thereto, said sleeve being so constructed and arranged with reference to said cup as to form an annular dead air space surrounding the same.
12. Ignition mechanism for a rotary oil burner including a rotatable oil cup comprising a fuel tube opening into said cup and constituting one electrode of an electric circuit, an electrode rod extending through said fuel tube into said cup, a resistance coil positioned within the oil cup on the discharge side of the opening in said fuel tube connecting the two electrodes, and a heat insulating sleeve surrounding said oil cup.
13. Ignition mechanism for a rotary oil burner including a rotatable oil cup comprising a fuel tube opening into said cup and constituting one electrode of an electric circuit, an electrode rod extending through said fuel tube into said cup, a resistance coil positioned within the oil cup on the discharge side of the opening in said fuel tube connecting the two electrodes, and an insulating sleeve surrounding said oil cup in spaced relation thereto, said sleeve being so constructed and arranged with reference to said cup as to form an annular dead air space surrounding the same.
14. Ignition mechanism for a rotary oil burner including a rotatable oil cup and a fuel tube opening into said cup, and comprising a heating element disposed within the cup in spaced relation to the wall thereof, and a heat insulating sleeve surrounding said cup.
15. Ignition mechanism for a rotary oil burner including a rotatable oil cup and a fuel tube opening into said cup, and comprising an electric heating element disposed within the cup in spaced relation to the wall thereof, and a heat insulating sleeve surrounding said cup.
16. Ignition mechanism for a rotary oil burner including a rotatable oil cup and a fuel tube opening into said cup, said mechanism comprising

ing a heating element positioned within said cup spaced from the wall thereof and on the discharge side of said fuel tube opening, and a heat insulating sleeve surrounding said cup.

5 17. Ignition mechanism for a rotary oil burner including a rotatable oil cup and a fuel tube opening into said cup, and comprising a heating element positioned within the cup on the discharge side of said fuel tube opening, and a heat insulating sleeve surrounding said cup, said sleeve being spaced from the wall of said cup.

10 18. Ignition mechanism for a rotary oil burner including a rotatable oil cup and a fuel tube opening into said cup, and comprising a heating element positioned within the cup on the discharge side of said fuel tube opening, and a heat insulating sleeve surrounding said cup, said sleeve being fixedly positioned in relation to said rotatable cup and spaced therefrom.

15 19. Ignition mechanism for a rotary oil burner including a rotatable oil cup and a fuel tube opening into said cup, and comprising an electric heating element disposed centrally within

the cup on the discharge side of said fuel tube opening, and a heat insulating sleeve fixedly positioned in surrounding relation to said cup.

20. Ignition mechanism for a rotary oil burner including a rotatable oil cup and a fuel tube opening into said cup, and comprising a heating element positioned within the cup on the discharge side of said fuel tube opening, an insulating sleeve fixedly positioned with reference to said cup and surrounding the same, said sleeve being so constructed and arranged with reference to said cup as to form an air space about the cup.

21. Ignition mechanism for a rotary oil burner including a rotatable oil cup and a fuel tube opening into said cup, and comprising a resistance coil positioned within the cup on the discharge side of the opening in said fuel tube, and an insulating sleeve surrounding said oil cup in spaced relation thereto, said sleeve being so constructed and arranged with reference to said cup as to form an annular dead air space surrounding the same.
